UNITED STATES PATENT OFFICE.

AUGUST M. AUGENSEN, OF MAYWOOD, ILLINOIS, ASSIGNOR TO SANITARY CAN COMPANY, OF NEW YORK, N. Y., A CORPORATION OF NEW YORK.

ARTICLE-FEEDING MECHANISM.

1,138,588.

Specification of Letters Patent.

Patented May 4, 1915.

Application filed May 13, 1912. Serial No. 696,895.

To all whom it may concern:

Be it known that I, AUGUST M. AUGENSEN, a citizen of the United States, residing in Maywood, in the county of Cook and State 5 of Illinois, have invented a new and useful Improvement in Article-Feeding Mechanism, of which the following is a specification.

This invention relates to feeding devices 10 for sanitary can bodies or similar articles.

The object of applicant's invention is to provide a compact, simple structure which may be easily attached to any of the common forms of can filling machines now in use, and 15 which will automatically time the feeding of the sanitary can bodies to the filling machine, and which will tip the can bodies from a position where the can bodies have their axes in a horizontal line to a position where 20 their axes extend in a vertical line.

The invention furthermore consists in the improvements in the parts and devices and in the novel combinations of parts and devices herein shown, described or claimed.

25 My improvements relate more particularly to devices for feeding what are commonly called flanged or "sanitary" cans to filling machines, that is,—cans having an open top and a laterally extending seaming flange as distinguished from the solder hole and cap cans. Although it has been customary in 30 canning factories to use vertical, gravity feed chutes for conveying the hole and cap cans to the filling machines, since no difficulty is experienced in feeding the same down the chute vertically one on top of the other and cutting out the lowermost can by a suitable reciprocating slide, yet with the open top or sanitary flanged can it has

35 hitherto been found impractical to use a gravity feed chute, since the flanges of the cans were likely to be damaged or dented, thus preventing the formation of a perfect, hermetic double seam and furthermore the 40 open top sanitary cans have a tendency to nest, which materially interferes with cutting out the bottom can from a stack. With my improvements, I feed the cans by gravity

45 down a chute with the axes of the cans horizontal and then tip or tilt the cans so that their axes assume a vertical position, one by one, just prior to the cans being pushed under the nozzles of the filling machines.

50 In the accompanying drawing forming a part of this specification, Figure 1 is a side

elevation of a structure embodying my improvements. Fig. 2 is an end view of the structure shown in Fig. 1, taken from the left as viewed in Fig. 1. Fig. 3 is a horizontal, sectional view, taken on the line 60 3—3 of Fig. 2, looking in the direction of the arrows, and Fig. 4 is a detail view upon a somewhat enlarged scale, of the ratchet mechanism.

In the drawing, 10 denotes a framework 65 or bracket which may be attached to any common form of can filling machine, and the same is provided with a pair of vertically extending arms 11 and 12, at the top of which is mounted a shaft 13 having a star 70 wheel 14 thereon, which is disposed over and preferably centrally of the lower end of a gravity feed chute 15, and by the term "chute" it will be understood that I mean any form of structure adapted to confine or 75 guide or limit the path of travel of the articles being fed, and as shown in the drawings, this gravity feed chute is composed of a plurality of bent iron bars 16, 16. This chute 15 terminates at and is secured to the 80 bracket 10 and also secured to said bracket or frame is a vertical chute 17, the same being preferably in the form of a casing having a cylindrical member 18 provided with a cut-out portion 19 on one side thereof, and 85 having formed integrally therewith a track composed of two rails 20 and 21, which terminate at the circumference of the cylindrical portion 18 at one end and at the opposite end form the continuation of the lower 90 side of the bottom of the vertical chute 15. Although the track is shown as composed of two separate rails, it will be understood that the same may be composed of a single piece having the edges thereof disposed in the 95 same manner as the rails 20 and 21. As more clearly shown in Fig. 2, the rail 21 is progressively elevated above the rail 20 in a direction leading over the bracket to the cylindrical portion 18. Guard rails 22 and 100 23 also extend from the bracket 11 to the upper portion of the cylindrical member 18 in order to confine the can bodies 24 as the latter pass from the gravity feed chute to the vertical chute. The star wheel which 105 forms a part of the timing mechanism for the can bodies or other articles is operated by means of a ratchet wheel 25 secured to the outer end of the shaft 13, spring controlled pawl 26 mounted on a lever 27, the 110

latter being loosely and rotatably mounted on the shaft 13 and adapted to be oscillated by means of an arm 28, formed integrally with a reciprocating slide member 29, 5 mounted on the bracket 10, the slide 29 being operated by means of a pivotally connected link 30 and crank 31, said crank 31 having an arm 32 adapted to be reciprocated by any suitable means, such as a slide 33 10 operated by means of a pitman 34 connected to gear 35 which may be connected to any portion of the driving means of the can filling machine.

In dotted lines in Fig. 1 is shown a slide 15 36, such as is usually found in connection with can filling machines, onto which the can bodies are adapted to drop through the vertical chute 17 and which, as will be understood, is operated in unison with the star 20 wheel or timing mechanism above described.

In operation, the can bodies feed down the gravity chute 15 and are arrested by the arms of the star wheel 14, which separates or spaces the can bodies sufficiently to prevent the same from jamming or interfering with each other during the tilting or tipping operation and allows the same to feed one by one to the vertical chute 17, and, as the can bodies travel over the track composed 25 of the rails 20 and 21, the open end of the cans which, as shown in Fig. 2, are on the right hand side, are tipped up by the rail 21, and just as the bottom of the cans reach the cylindrical portion 18, the can bodies will 30 be tipped up to a vertical position and will drop through the chute onto the slide 36.

As will be apparent to those skilled in the art, many changes may be made in the details of my improvements without departing 40 from the spirit of the invention, and all such changes and variations are contemplated as fall within the scope of the claims appended hereto.

I claim:—

45 1. A feeding device for can bodies comprising in combination, a gravity feed chute, a vertical chute and a track connecting said chutes over which the can bodies are adapted to pass, said track having two rails, one of 50 which is elevated progressively relatively to the other to thereby tilt the can bodies, and timing mechanism for spacing the can bodies as they leave the gravity feed chute, sufficiently to allow them to pass onto said track 55 and be tilted, one at a time, into the vertical chute without jamming or interfering with each other, substantially as specified.

60 2. A feeding device for can bodies comprising in combination, a gravity feed chute and a vertical chute, a track located between said chutes and over which the can bodies are adapted to pass, said vertical chute having a cylindrical portion, and said track having two rails, one of which is elevated progressively relatively to the other, said rails

terminating at the circumference of the cylindrical portion of the vertical chute.

3. In a device for feeding can bodies in combination, a gravity feed chute and a vertical chute and means for automatically tipping the can bodies being fed while passing from the gravity feed chute to the vertical chute, said vertical chute having a cylindrical portion provided with cut-out section on one side thereof.

4. In a device for feeding can bodies in combination, a gravity feed chute, a cylindrical vertical chute and means for automatically tipping the can bodies being fed while passing from the first named chute to the last named chute, said means including a track formed with the cylindrical chute, said chute being provided with a cut-out portion on the side adjacent said track, substantially as specified.

5. A feeding device for can bodies comprising, in combination, a frame-work adapted to be attached to a machine, a gravity chute terminating and secured to said framework, a vertical chute also connected to said framework and a track portion between said chutes over which the can bodies being fed are adapted to pass, said track having one side thereof elevated above the other side, and timing mechanism for separating and spacing the can bodies as they leave the gravity chute sufficiently to allow the same to be tilted into the vertical chute, one at a time, without jamming or interfering with each other, substantially as specified.

6. In a device for feeding sanitary can bodies, in combination: a downwardly extending chute in which the can bodies are arranged with their axes horizontal, and resting on one another side to side so as to move by gravity, the lower end of said chute being turned to extend in a substantially horizontal direction; a track extending from said horizontal portion of the downwardly extending chute, one side of said track sloping downwardly relative to the other side; a can body guide located at the higher side of said track, said guide turning off laterally to direct the can body laterally as it is advanced; and a vertical chute leading downward from an aperture, with which it is formed at the termination of the track and guide.

7. In a device for feeding sanitary can bodies, in combination: a downwardly extending chute in which the can bodies are arranged with their axes horizontal, and resting on one another side to side so as to move by gravity; a vertical chute for receiving the can bodies one at a time with their axes arranged vertically and their open ends up; a track and can guiding means leading from the lower end of the downwardly extending chute to the said vertical chute, and ar-

ranged to tilt the cans successively from horizontal to vertical position; and a positive can feeding device arranged between the lower end of the downwardly extending chute and the point where the cans are tilted, and acting to regulate the movement of the cans in the downwardly extending chute, and acting to push the cans along and against the said track and can guiding means and to the downwardly extending chute.

8. In a device for feeding sanitary can bodies, in combination: a downwardly extending chute in which the can bodies are arranged with their axes horizontal, and resting on one another side to side so as to move by gravity, the lower end of said chute being turned to extend in a substantially horizontal direction; a track extending from said horizontal portion of the downwardly extending chute, one side of said track slop-

ing downwardly relative to the other side; a can body guide located at the higher side of said track, said guide turning laterally to direct the can body laterally as it is advanced; a vertical chute leading downward from the said aperture and having an aperture at the end of said track and guide; and a positive can feeding device arranged between the downwardly extending chute and the point where the cans are tilted by the track, and acting to regulate the movement of the cans in the downwardly extending chute, and acting to push the cans along and against the said track and can guiding means and to the aperture of the downwardly extending chute.

AUGUST M. AUGENSEN.
